[57] CLAIM

The ornamental design for a jewelry clasp, as shown and described.

DESCRIPTION

FIG. 1 is a top, right front perspective view of a jewelry clasp showing my new design;

FIG. 2 is a perspective view of the other three sides;
FIG. 3 is an exploded perspective view in the same orientation as FIG. 1;

FIG. 4 is an exploded perspective view in the same orientation as FIG. 2; and

FIG. 5 is a right end view of the receptor element alone. The broken lines showing typical eyelets are for illustrative purposes only.
